CENTRIFUGAL SWITCH STRUCTURE

Raymond Reger, Anderson, Ind., assignor to The
Pierce Governor Company, Inc., Anderson, Ind.,
a corporation

Application July 12, 1947, Serial No. 760,666

7 Claims. (Cl. 200—80)

1

This invention relates to an overcenter operable switch structure.

The chief object of this invention is to provide a speed responsive switch that does not fluctuate to and fro in making contact and breaking contact at the critical speed, which action is commonly called "hunting," the switch thus making contact and maintaining contact at a critical speed and breaking contact and maintaining open circuit condition at any other speed on the same side of the critical speed, as for example lower speeds.

Obviously the invention can be arranged to open a circuit instead of close a circuit at critical speed, this being a reverse arrangement. The circuit herein can be utilized for direct power control or for pilot control, that is, in a remote control system. The present disclosure of the invention is represented as a centrifugally operable switch device.

The chief feature of the present invention resides in providing an oscillatable arm or fork and an arm including a switch member of a snap action type so that switch "hunting," if any, within a very slight variation of force, at the critical or predetermined force will not reversely actuate the switch.

Other objects and features of the invention will be set forth more fully hereinafter.

The full nature of the invention will be understood from the accompanying drawings and the following description and claims.

In the drawings—

Fig. 1 is a side elevation of a centrifugally operable switch structure embodying the invention, the cover plate being removed.

Fig. 2 is a plan view of the invention, the switch housing being shown in section.

Fig. 3 is a view similar to Fig. 1 and of a modified form of the invention.

Fig. 4 is a view similar to Fig. 2 and of the form shown in Fig. 3, the major portion of the centrifugal portion being omitted.

In Fig. 2 of the drawings there is illustrated in dotted lines the interior mechanism of a centrifugal governor such as illustrated, described and claimed in copending application Serial No. 642,149 filed January 19, 1946 and entitled Compact Centrifugal Governor, which application was subsequently abandoned, and formally made a part hereof, which mechanism generally will be hereinafter more fully referred to.

In Fig. 1, 10 indicates a housing generally and from which projects a rock shaft 11. The housing may include the exterior chamber forming

2

walls 12 and suitably secured within the chamber is bracket 13 having spaced arms 14 and 15 provided with aligned apertures.

5 A threaded stem 16 is disposed therein and mounts a lock nut 17 at one end and terminates in eye 18 at the opposite end. A concentric spring 9 at one end bears upon arm 14 and at its opposite end bears upon stop 19 carried by stem 16 between the arms.

10 Rock shaft 11 has rigidly secured to it within said chamber the insulation block 20^a to which is secured the arm 20. This arm is provided with a longitudinally disposed series of apertures 21. Secured to eye 18 is one end of a spring 22, the 15 other end 22^a being selectively associated with the desired aperture 21. Spring 22 is the governor load spring and its force is adjusted by advancing or retracting the stem 16 toward and away from arm 20. Other adjustment is effected 20 by selecting the desired aperture 21 for spring mounting purposes.

Block 20^a has disposed in transverse relation to the longitudinal axis of arm 20 a pair of spaced stops 23 and 24. These are offset radially from 25 the shaft. Stop 24 includes contact 25 and connected thereto is pigtail 26, same being connected to insulated terminal 27 carried by wall 12.

Disposed between the stops is a contact 28 carried by portion 29, see Fig. 2, of a member 30 having spaced arms 30 and intermediate arm 31. The outer arms are bowed and the intermediate arm is generally straight. An insulation block 32 is suitably secured within the chamber as at 33 and carried thereby is the U-shaped conductor having arms 34 notched on the ends at 35, see Fig. 1, and the midportion 36 disposed in contact with the extended portion of arm 31. Arms 30 are fulcrumed in notches 35. A connecting screw 37 serves as an anchor for terminal strip 38 connected to insulated terminal post 39 also carried by wall 12 of the chamber.

40 The resulting structure is a snap action switch actuated by rock shaft 11 upon counter-clockwise rotation in opposition to load spring 22 and 45 in accordance with centrifugal force of the governor generated in accordance with or proportional to the power speed.

The switch is so arranged that the circuit is 50 normally open below governed speed and at governed speed the circuit is closed by the switch. This is effected as follows: As the stop 23 moves counter-clockwise, contact 28 is carried therewith. When carried beyond the equilibrium or central position, the member 29 snaps overcenter

and contact 28 immediately engages terminal member 25 to complete the circuit.

Obviously if member 25 were applied to stop 23 instead of stop 24 the switch would be normally disposed in closed circuit condition and snap overcenter to the open circuit condition.

Reference will now be had to Figs. 3 and 4. Herein the governor housing 110 has projecting from same into the chamber formed by walls 112, the governor or speed responsive rock shaft 111 10 which mounts slightly arched arm 120 having two concentric series of holes 121, same being staggered as shown.

Load spring 122 has its end 122a selectively associated with the desired hole 121 for proper adjustment. The other end of said spring is secured in aperture 118 in the confronting end of member 116. Bracket 113 includes spaced guide portions 114 and 115 and member 116 is secured in adjusted position by nut 117.

Concentric with member 116 is spring 109 which bears at one end against portion 114 and at its opposite end upon retainer 119 fixed to member 116. The general similarity of this form to that shown in Figs. 1 and 2 will be obvious.

Rigid with arm 120 and shaft 111 is a transversely disposed arm 120a and same mounts stop pins 123 and 124 spaced apart as shown. The latter may have suitably secured to it contact 125 electrically connected by pigtail or like member 126 to insulatedly mounted terminal post 127.

Wall 112 of the chamber insulatably supports terminal post 139 and lead 138 is connected to terminal screw 137 carried by current conducting member 132 insulatably secured as at 133 and 35 133a to the back wall of the chamber.

Herein member 132 includes portion 134 grooved as at 135. A pair of flat spring arms 130 are pivoted therein and the opposite ends terminate in a common portion 129 carrying contact 128, the latter and the free end of portion 129 being disposed between stop 123 and 124 for selective operative contact therewith.

Disposed parallel to portion 134 of member 132 is a similar portion 136 apertured at 136a to take one end of spring 131, the other end being elongated at 131a to extend through aligned aperture 134a, the other end being anchored as at 129a to switch portion 129.

The switch construction hereof operates similar to that shown in Figs. 1 and 2 but is simpler and has a longer life. Spring 131 is the tension overcenter maintaining and biasing force providing means. Arms 130 and midportion 129 with contact 128 constitute the switch element that snaps overcenter to closed and open circuit positions depending upon the movement of speed responsive rock-shaft 111. If desired the spring 131 may have its end adjustably anchored to bracket portion 136 in any well known manner, to wit, an eye bolt threaded in aperture 136a and locked by a nut if desired.

In Fig. 2, 40 indicates a speed driven member mounted on a shaft 41 rotatably supported in the housing 10. A sleeve 42 is slidable on said shaft and is operatively associated with race structure 43 that is engaged by yoke 44 carried by said shaft 41. Shaft 41 mounts plate or spider 45 to which is pivoted at 46 weight members 47, the tails 48 of which bear against the adjacent end of sleeve 42.

Normally load spring 22 constrains the shaft 11, yoke 44, and sleeve 42 to the position wherein the weights 47 are collapsed toward the shaft 41 and sleeve 42. When the speed of shaft 41 is

sufficient, centrifugal force overcomes the force of the load spring 22 and the rock shaft 11 is rocked or oscillated. This occurs at the predetermined speed.

Since shaft 11 movement is gradual or progressive in the neighborhood of governed speed, speed fluctuation would alternately open and close the circuit due to hunting and surging. Snap action, herein, insures that the desired circuit is effected at the desired speed, alternate circuit reversals in the neighborhood thereof are prevented, and in opening the circuit, the arc does not hang on but immediately dies out, thus prolonging the life of the contacts 25-28 or 125-128. This means that high cost, long life, arc resisting contacts are not necessary.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a device of the character described, in combination, a centrifugally operated rock shaft, an arm carried by said shaft and extending at an angle to the axis of said shaft, a biasing spring having one end stationarily anchored and the opposite end connected to said arm, a pair of spaced apart stop arms carried by said shaft extending at an angle to said arm and rockable by said shaft, a contact mounted on one of said stops, a flexible plate contact carrying arm rigidly supported at one end and having a free end disposed between said stop arms and movable by said stop arms in opposite directions by said stop arms when the same are rocked by the rocking movement of said shaft and means for biasing the free end of said plate in either direction when the plate is moved past dead center in either direction by engagement with said stop arms.

2. In a device of the character described in combination a centrifugally operated rock shaft, an arm carried by said shaft and extending at an angle to the axis of said shaft, a biasing spring having one end stationarily anchored and the opposite end connectible at variable points along the length of said arm, a pair of spaced apart stop arms carried by said shaft extending at an angle to said shaft and rockable by said shaft, contact means mounted on one of said stop arms, a flexible plate contact carrying arm rigidly supported at one end and having its free end disposed between said stop arms and movable by said stop arms in opposite directions when the same are rocked by the rocking movement of said shaft, and means for biasing the free end of said plate in either direction when the plate is moved past dead center in either direction by engagement of said stop arms.

3. In a device of the character described in combination, a centrifugally operated rock shaft, an arm carried by said shaft and extending at right angles to the axis of said shaft, a biasing spring having one end adjustably stationarily anchored and the opposite end connected to said arm, a pair of spaced apart stop arms carried by said shaft extending at an angle to said shaft and rockable thereby, a contact mounted on one of said arms, a flexible plate contact carrying

arm rigidly supported at one end and having its free end disposed between said stop arms and movable by said stop arms in either direction and movable by said stop arms in opposite directions when the same are rocked by the rocking movement of said shaft and means for biasing the free end of said plate when the plate is moved past dead center in either direction by engagement of said stop arms.

4. A switch assembly comprising a centrifugally movable non-rotatable rock shaft, centrifugally operable rotative means for rocking the shaft, angularly disposed arms oscillatable thereby, a pair of supports, one being in general alignment with the longitudinal axis of one of the arms and the other support being directed substantially transverse to the similar axis of the other arm, a load spring operatively connected at one end to the said other arm and at its opposite end to the support directed transverse there-to and normally opposing rocking of the shaft by the said first mentioned means, to and fro movable switch means carried by the said one support and directed toward the arm aligned therewith, spaced stops determining the extent of the to and fro movement, spring means biasing the switch means to either of the to and fro positions when moved toward the same and beyond

10

5

15

the median position therebetween, and a contact member disposed for switch means engagement in one of the to and fro positions.

5. A switch assembly as defined by claim 4 wherein the stops are shaft movable and the switch means is alternately movable by the stops.

6. A switch assembly as defined by claim 4 wherein the contact member is shaft movable.

7. A switch assembly as defined by claim 5 wherein the contact member is also shaft movable.
